UNITED STATES PATENT OFFICE.

FRANK R. McBERTY, OF GALION, OHIO, ASSIGNOR TO THE NORTH ELECTRIC MANUFACTURING COMPANY, OF GALION, OHIO, A CORPORATION OF OHIO.

TELEPHONE-EXCHANGE SYSTEM.

Application filed March 15, 1920. Serial No. 365,921.

To all whom it may concern:

Be it known that I, FRANK ROBERT McBERTY, a citizen of the United States, residing at Galion, in the county of Crawford 5 and State of Ohio, have invented certain new and useful Improvements in Telephone-Exchange Systems, of which the following is a specification.

This invention relates to telephone exchange systems and particularly to telephone systems in which machine switching equipment is employed.

The principal objects of the invention are to provide fast and reliable controlling and 15 actuating means for machine switching equipment, and to devise a new and useful method for handling multi-office connections, such as connections between a private branch and a city exchange.

With these objects in view, new and useful features have been embodied into a telephone system. The following are some of 20 these features:

Mechanisms used for controlling the operation of machine switches employed in the establishment of telephone connections are dissociated from their operative relation with machine switches upon the completion of the contemplated connection. The mechanisms 25 are preferably counting relays arranged at the central exchange to "count" or register impulses sent from a calling station, but the invention is applicable to impulse producing, sending, recording or registering equipments of varied types and location.

The association of the mechanisms, such as counting relays, with a connecting link is controlled by a testing means, such as a 30 test relay, associated with a machine switch used in the establishment of connections and operated depending on the busy or idle condition of called subscribers' or trunk lines. In accordance with a further feature, if the 35 called line is found busy, the testing means actuates apparatus for informing the calling party of this fact.

The advantages of the provision of these features consist in the immediate detachment of the counting relays, after but not before the correct and complete operation of the machine switches has been insured. By giving the testing means control of the 45 busy signal and the dissociation of the counting relays, the calling party is

promptly informed of the impossibility of obtaining the desired connection. Still a further advantage of these arrangements resides in the simplified controlling circuits and reduced number of relays and other apparatus that result from adoption. 60

Two switches, such as an automatic trunk or line selecting switch, by means of which the calling line is extended upon the initiation of the call, and a selector or connector switch may be restored or released to their normal inoperative condition after, and also prior to, the complete establishment of a telephone connection by these switches if, for instance, it becomes necessary to re-route a call. The means by which the restoration of the switches is controlled prior to the completion of the connection is common to a plurality of lines. 65 70

The restoration of two switches, such as the above mentioned switches, is controllable at a common point, whereby all or any one of the parties to a connection may be given control over the restoration of the connection without the necessity of providing additional apparatus for this purpose, and, furthermore, the whole connection may be instantaneously annulled to give room to the establishment of a new connection. 75 80

A new and useful impulse receiving device in the form of counting relays is provided. The counting relays are arranged to make possible the rapid sending of impulses, the immediate setting or control of switching devices associated with the counting relays, and the consumption of a minimum amount of current during the operation of these relays. All this is made possible due to the correlation between the various counting relays, and the correlation between the 85 90 95 counting relays and the rest of the system.

Means are provided for establishing and maintaining a connection between calling and called lines. If the called line is idle, direct connection to the line is made. If it is busy, the connection is not disestablished but is simply maintained open, preferably by a test relay. As soon as the called line becomes idle, the test relay operates and completes the connection. If the calling party does not want to wait until the called line becomes idle, he may operate means, e. g. by hanging up his receiver, for completely restoring the connection. 100 105

Inter-office connections, such as connec- 110

2

tions from a private branch exchange line to a city line, are established in the following manner: First, a connection local to the calling exchange, e. g. private branch exchange, is partially established. When, in the course of the establishment of this local connection, it becomes evident that a connection with another exchange is desired, the partially established local connection is 5 annulled. The fact that an inter-office and not an intra-office connection is desired is preferably indicated by the sending of local switch controlling impulses representing a digit characteristic for an inter-office line. 10 After the complete restoration of the local connection, another switch is operated to extend the calling line towards the called line associated with the distant exchange. The last mentioned switch is preferably so 15 arranged that its actuation is caused by means operated in response to the initiation of the call, and in accordance with a further feature of the invention, the mentioned means are brought into operative relation with the switch at the time of the 20 restoration of the local connection.

Due to this method of handling multi-office connections, the circuits and apparatus required are simplified, and inter-office connections are obtainable at a relatively great speed. In addition to the apparatus necessary for local connections, only a few relays, with their controlling circuits, and a line switching device need be provided for 30 multi-office traffic. In accordance with further features of the invention, this additional device may be used for the double purpose of extending a line as a calling or called line, and the additional relays co-operate also in the establishment of purely local 35 connections.

One of the switches used in the establishment of connections, preferably the inter-office connections, is a two-way switch, i. e. 40 one operable to extend connections from a line used as a calling line, and to this line when called. When the two-way switch is used to extend a connection from a calling line, it is automatically operated in response 45 to the initiation of the call to connect with an idle trunk line. When this switch is used as a connector to extend a connection to the mentioned line as a called line, it is operated at the will of a calling party, such as 50 an operator at the private or city exchange, or subscriber.

A two-way trunk, i. e. one through which connections may be established in both directions, is provided. In accordance with 55 the present exemplification of the invention, the two-way trunk co-operates with the mentioned two-way switch, and is used for interconnecting two exchanges, such as a private branch exchange with a city exchange. A signaling means, such as a ring-

ing current generator, is associated with the two-way trunk. This generator is connected to ring a line connected with the trunk, but only if this line is a called and not if it is a calling line. Preferably, the means used 70 for preventing the operation of the generator is actuated under the control of the switch, such as the two-way switch, by means of which the line in question is connected with the trunk. 75

A testing means, such as a test relay preferably associated with the two-way switch, is operable to control the discrimination between calling and non-calling, and idle and busy lines. The test relay controls the actuation of a busy signal at an operator's position associated with the two-way trunk, and co-operates in the control of the mentioned means controlling the application of ringing current to a called line. 85

In accordance with the preferred embodiment of the invention, the various machine switches used in the establishment of connections are relays having a plurality of contacts. The relays herein disclosed are 90 of the type described in Patent No. 1,189,891 to H. G. Webster dated July 4, 1916. The various features of the invention are, of course, not limited to relay selectors of this or any other type, and the advantages of 95 these features may be readily derived by using them in conjunction with widely varying types of switching devices. However, special advantages are derived from the combination of these features with relay 100 switching devices. This is particularly true for the two-way switch. While the adaptation of other types of switching devices for two-way working involves the addition of considerable apparatus and complicated circuits, the switching relay, in accordance with the present invention, is adapted for this purpose by the mere duplication of its controlling relay. In this connection, it should be understood that the new and useful means employed for combining the various features of this invention with relay 110 selectors may be used to advantage in applying such features or their equivalents to various other types of switching devices. 115

While in the present embodiment of the invention it is contemplated to provide one set of counting relays for each trunk, such counting relays or other impulse receiving or registering apparatus may be provided 120 in common for a plurality of trunk or connecting circuits and associated with one of these circuits upon its seizure by a calling line. Arrangements of this character are well-known in the art. 125

These and other features of the invention will be more readily understood from the following description of the operation and arrangement of the telephone system and the appended claims. 130

In the drawings, Fig. 1 illustrates calling and called lines of a private branch exchange, together with switching apparatus by means of which the lines may be interconnected; Fig. 2 illustrates the circuits of a set of counting relays; Fig. 3, a two-way trunk leading to a city exchange, together with its selecting and controlling apparatus; and Fig. 4, the connecting circuit of a city exchange operator. When tracing the circuits, Fig. 2 should be placed below and Fig. 3 above Fig. 1. Fig. 4 should be placed to the right of Fig. 3. The illustration in the drawings is schematic and abbreviated for the purpose of clearness and simplicity. The arrangement of those parts of the telephone system which are not illustrated in the drawings and their co-operation and connection with the illustrated portions will be fully set forth in the following general description. After the general description, a detailed description will be given of the establishment of a connection within the private branch exchange, and of connections between the city exchange and the private branch exchange.

General description of the system.

Subscribers' lines associated with the private branch exchange (Fig. 1) are interconnected by means of digital sets of switching relays, such as 130 and 140, responsive to the initiation of the call, and similar sets of switching relays, such as 160 and 170, operable by counting relays (Fig. 2). The counting relays are variably adjustable and are controlled by the calling subscriber in accordance with the numerical designation of the called line. All the switching relays are arranged like the ones illustrated in the drawings. Of the switching relays, 130 carry answering and 170 calling terminals of the lines. All the answering terminals of a line are multiplied with each other and with the multiplied calling terminals of the respective line. The mentioned answering and calling terminals comprise a set of three contacts, through which the two talking conductors and the test conductor of a line may be connected with trunk lines or connecting links, such as A. The number of such trunk lines depends on the requirements of the traffic, approximately one trunk line being provided per ten subscribers' lines. Each trunk line is arranged like A and is provided with a set of counting relays like the one illustrated in Fig. 2.

Each subscriber's line is provided with line and cut-off relays like 109 and 107. The left-hand armatures of all the line relays 109 are multiplied to the winding of relay 110 common to all the lines of the private branch exchange. The inner right-hand armatures of all the cut-off relays 107 are multiplied to the back contact of relay 111 common to

all the lines. In exchanges of large capacity, the lines should be divided into groups and each group provided with relays like 110 and 111.

Each trunk, like A, is provided with one relay like 113 controlling the connection to city trunks. The left-hand front contacts of all relays 113 are multiplied to the left-hand back contact of the relay 110. The right-hand front contacts of all the relays 113 are multiplied to the armature of a relay 302.

Each trunk, like A, is provided with a relay like 112, the busy or idle condition of a trunk being indicated by the energized or de-energized condition of its relay 112. The armatures and front contacts of these relays are interconnected in a manner shown in connection with relays 112, 112^a and 112^b, to form an extended starter wire circuit operating in the control of the line switching relays to connect the calling line with an idle connecting or link circuit.

Each trunk is provided with a multi-contact switching relay like 120. The left-hand contacts of each relay 120 are divided into two groups of ten contacts. The contacts in one group represent units digits 1-0, and the contacts of the other group represent tens digits 1-0. Depending on the numerical designation of the associated subscriber's line, the right-hand contacts of each line relay are connected to a certain tens and a certain units contact of each relay 120 for the purpose of identifying the numerical designation of the calling line.

In exchanges having a capacity of more than one hundred lines, as many relays 120 and 112 should be provided per trunk as there are 100-line groups, the front contacts of a group of line relays being multiplied only to the contacts of certain relays 120 and the armature of a certain relay 112. One switching relay like 130 is provided for each trunk to connect it with a certain group of ten subscribers' lines, there being as many relays as there are groups of ten subscribers' lines and each relay being provided with 31 contacts. Each subscriber's line is identified by three contacts, like 132, 133 and 134, on the tens relay 130.

Each trunk line is provided with ten units switching relays like 140. The right-hand tens group of contacts of the relays 120 are connected in numerical order to the windings of the tens relays 130, the first contact being connected to the relay 130 serving lines 10-19, the second contact to the relay 130 serving lines 20-29, etc. In a similar numerical order, the right-hand units group of contacts of the relays 120 is connected to the windings of the various units relays 140. In this manner, upon the initiation of a call, the calling line is extended to an idle trunk by means of a pair of relays 130.

like 130 and 140, representing the tens and units digits of the calling line number. The right-hand contacts of the relays 130 are connected to the left-hand contacts of a certain relay 140 associated with each trunk. The right-hand contacts of all the relays like 140 that represent the same trunk are multiplied to the conductors of the trunk with which the respective relays are associated.

In numerical arrangement, the relays 170, representing the tens digits, correspond to the relays 130, and the relays 160, representing the units digits, correspond to the relays 140. That is to say, each trunk line is provided with one relay like 170 per ten subscribers' lines and ten relays like 160.

The right-hand contacts of relays 170 are connected to the subscribers' lines in the same manner as the left-hand contacts of the relay 130. As in the case of relays 130 and 140, the left-hand contacts of the relays 170 are connected by threes to the right-hand contacts of the various relays 160, representing the units digits of the respective line. The left-hand contacts of the relays 160 are multiplied to the conductors of the associated trunk.

Each private branch exchange trunk is provided with a relay 190 and a relay 180. The left-hand contacts of these relays are connected to the conductors leading to the lowermost contacts of the counting relays 213, 215, 217, 219, 221, 223, 225, 227, 229, and 231 in the following manner; the first contact to relay 213, the second to 215, etc., and the tens contacts to relay 231. The right-hand contacts of the relays 190 are connected in numerical order to the windings of the relays 170, representing the various tens digits of the line numbers. The right-hand contacts of the relays 180 are connected in numerical order to the windings of the various relays 160 of the associated trunk, representing the various units digits of the line numbers.

The private branch exchange is connected with the city exchange by means of two-way trunks like the one illustrated in Fig. 3. Each two-way trunk is provided with a relay 302. The various relays 302 are related to each other in the same manner as the relays 112. These relays control the association of a calling line with an idle city or inter-office trunk. Each city trunk is provided with a switching relay like 350, the lower contacts of which are connected to the front contacts of the line relays of subscribers entitled to outside or city connections in the same manner as the connections to the left-hand contacts of relay 120.

Each ten lines entitled to city connections are provided with a relay 360 per trunk and are connected with the left-hand contacts of these relays in the same manner as with the

left-hand contacts of the relay 130. Each city trunk is provided with ten relays like 370. The relation between relays 360 and 370 is the same as between relays 130 and 140. The upper contacts of the relays 350 are connected with the windings of the relays 360 and 370 in the same manner as the right-hand contacts of the relays 120 are connected with the windings of the relays 130 and 140.

One or several operators' positions are provided for handling city connections. The operator's position is equipped with a telephone set 355, which may be connected with any one of the city trunks handled by the operator, by means of listening-key contacts 324, 325, one set of such contacts being provided for each city trunk. The operator's position is further provided with a calling lamp 330, a ringing lamp 331, and a busy lamp 334 for each city trunk handled by the operator. Key-contacts 332, 333 are provided for each city trunk.

One switching relay 380 per city trunk is connected with the associated key-contacts 333. Each operator's position is equipped with a keyboard sender, comprising keys like 340—343. The sender is composed of as many rows of interlocking keys as there are digits in the line-numbers of the private branch exchange. Each row comprises a key for each of the ten numerals of the particular digit. Depending on their numerical designation, the outer contacts of the keys are connected with the various lower contacts of the relays 380. In corresponding order, the upper contacts of the relays 380 are connected with the windings of the various relays 360 and 370 representing the lines. The inner contacts of the keys are connected in multiple to the various key-contacts 333 at the particular operator's position.

It should be noted that the number of the switching relays depends on the capacity of such relays, the mentioned figures being reached with relays having a capacity of not more than thirty-one contacts.

ESTABLISHMENT OF PRIVATE BRANCH EX- CHANGE CONNECTIONS.

Selections of idle connecting circuit.

The calling subscriber at station 100, desiring to initiate a call, removes his receiver from the switch-hook, whereupon a circuit is closed from grounded battery through a resistance 108, the left-hand armature and back contact of cut-off relay 107, conductor 105, calling device 104, transmitter 102, the make contact of switch-hook 101, conductor 106, the outer right-hand back contact and armature of the relay 107, and the winding of a line-relay 109 to ground. The relay 109 becomes energized and closes a circuit from ground, through the winding of group-

relay 110, the left-hand armature and front contact of relay 109, the inner right-hand armature and back contact of relay 107, the back contact and armature of relay 111, the 5 left-hand back contact and armature of relay 112, and the winding of relay 120 to grounded battery. The relays 110 and 120 become energized. The former performs functions to be hereinafter set forth, and the latter 10 closes circuits from ground, through the windings of relays 130 and 140, contacts 122 and 121 of relay 120, and the right-hand front contacts and armatures of relay 109 to grounded battery. The relays 130 and 140 15 become energized and close a circuit from ground, through the inner right-hand armature and back contact of relay 113, the winding of a slow-acting relay 114, contacts 142 and 132 of relays 140 and 130, conductor 106, the calling substation apparatus, conductor 105, contacts 134 and 144 of relays 130 and 140, and a retardation coil 150 to grounded battery. The relay 114 becomes 20 energized and closes the following circuits 25 in parallel; from grounded battery, through its inner armature and front contact, the winding of slow-acting relay 112 to ground; through the right-hand outer armature and back contact of relay 113, resistances 139 and 149, the contacts 131 and 141 and the 30 windings of relays 130 and 140 to ground; and through contacts 143 and 133 of relays 140 and 130, and the winding of relay 107 to ground. As a result of the closure of 35 these paths, the relays 107 and 112 become energized and the relays 130 and 140 are locked up through a circuit independent of the contacts of relay 120. The relay 107 opens the circuit of relay 109, whereupon 40 the latter becomes de-energized and causes in turn the de-energization of relays 110 and 120. Due to the closure of the relatively low resistance path through the relay 107, the potential on the multiple test terminals 45 is reduced to guard the line against seizure in a manner to be hereinafter described.

If another call is initiated at this time, then the relay 112 being energized, the line-relay 109^a of the second calling line connects ground through the winding of the relay 110, the left-hand armature and front contact of the line-relay 109^a of the second calling line, the middle back contact and armature of the cut-off relay 107^a of the 50 second calling line, the back contact and armature of the relay 111, the left-hand armature and front contact of the relay 112, the left-hand armatures and front contacts of all the energized relays corresponding to 112, the left-hand armature of the first idle relay, e. g. 112^a, and the winding of relay 120^a to grounded battery. The relay 120^a becomes energized and causes, through the agency of another pair of relays 55 corresponding to 130 and 140, the extension

of the second calling line to another connecting circuit. It should be noted at this point that the relays 112 remain in a de-energized condition as long as the trunks with which they are associated are idle. 70

Tens selection.

Upon the energization of the relay 112, a circuit is closed from grounded battery through the front contact and armature of this relay, the winding of a connecting relay 151, and the left-hand back contact and armature of relay 179 to ground. The relay 151 becomes energized and operatively connects the normally dissociated counting 75 relays (Fig. 2) with the trunk A to which the counting relays are individual. A circuit is closed from ground through the windings of relays 201 and 202, conductor 157, the upper front contact and armature of the relay 151, relay contacts 142 and 132, conductor 106, the circuit through the calling substation, conductor 105, relay contacts 134 and 144, and retardation coil 150 to 80 grounded battery. The relay 201 and, somewhat later, the slow-to-pull-up relay 202 become energized. The relay 202 closes a circuit from ground through the winding of relay 203, the upper back contact and armature of a relay 204, the front contact 85 and armature of relay 202, conductor 156, the middle front contact and armature of the relay 151, and the outer front contact and armature of the relay 114 to grounded battery. The relay 203 becomes energized and 90 closes a locking circuit for itself through its upper front contact and armature, and conductor 156, which circuit is independent of the contacts of relays 202 and 204. The relay 201 closes a circuit from ground 95 through the winding of relay 211, the upper back contacts and armatures of relays 210, 212, 214, 216, 218, 220, 222, 224, 226, and 228 in series, the front contact and armature of relay 201, the lower armature and back contact of relay 208, conductor 156, the 100 middle front contact and armature of relay 151, and the outer front contact and armature of the relay 114 to grounded battery. The relay 211 becomes energized and locks 105 up through its upper front-contact and armature the upper back contacts and armatures of the relays 213, 215, 217, 219, 221, 223, 225, 227, 229, and 231 in series, the upper back contact and armature of relay 208, conductor 156, the middle front contact and armature of the relay 151, and the outer front contact and armature of the 110 relay 114 to grounded battery. 115

The calling subscriber operates now his 125 calling device in accordance with the numerical designation of the called line. Assuming that this number is 41, the circuit extending through the calling station 100 is four times interrupted by means of 130

the calling device 104. The relay 114, being of the slow-to-release type, maintains its armature attracted during the production of these relatively short circuit interruptions. The relay 202, however, is quick to release its armature, whereby upon the first interruption of the line circuit, this relay closes a circuit from ground, through the winding of relay 204, the middle back contact and armature of the relay 205, the lower front contact and armature of the relay 203, the back contact and armature of the relay 202, conductor 156 and then to grounded battery at the armature of the relay 114. The relay 204 becomes energized and locks up through its lower front contact and armature and the conductor 156. Each interruption and closure of the line-circuit affects the relay 201, and upon the first opening of the circuit this relay becomes de-energized and establishes a circuit from ground through the winding of relay 210, the lower front contact and armature of the relay 211, the lower back contacts and armatures of the relays 213—231 in series, the back contact and armature of the relay 201, the lower armature and back contact of the relay 208, conductor 156, and then to grounded battery at the armature of the relay 114. The relay 210 becomes energized and locks up, through its lower front contact and armature, the lower back contacts and armatures of the relays 212—228 in series, the upper back contact and armature of the relay 208, conductor 156, and then to grounded battery at the armature of the relay 114.

Upon the following closure of the line-circuit by the calling device, the relay 201 becomes energized, but, due to the relatively short duration of the circuit closure, the slow-to-pull-up relay 202 remains de-energized.

In response to the energization of the relay 201, a circuit is closed from ground through the winding of relay 213, the upper front contact and armature of relay 210, the upper back contacts and armatures of the relays 212—228 in series, the front contact and armature of the relay 201, the lower armature and back contact of the relay 208, conductor 156, and to grounded battery at the relay 114. In its upper back contact, the relay 213 opens the locking circuit of relay 211, whereupon the latter becomes de-energized. The relay 213 closes a locking circuit for itself through its upper front contact and armature, the upper back contacts and armatures of the relays 215—231 in series, the upper back contact and armature of the relay 208, and conductor 156 to grounded battery at the relay 114.

Upon the next interruption of the line-circuit, the relay 201 closes a circuit from ground through the winding of relay 212,

the lower front contact and armature of the relay 213, the lower back contacts and armatures of the relays 215—231 in series, the back contact and armature of relay 201, and then to ground at the armature of relay 114. The relay 212 becomes energized and locks up through a circuit including the lower back contacts and armatures of the relays 214—228. In its lower back contact, the relay 212 opens the locking circuit of relay 210 and the latter becomes de-energized.

Upon the following closure of the line-circuit, the relay 201 is re-energized, the relay 202 remaining unaffected. The relay 201 closes a circuit from ground through the winding of relay 215, the upper front contact and armature of the relay 212, the upper back contacts and armatures of the relays 214—228 in series, the front contact and armature of the relay 201 to grounded battery. The relay 215 becomes energized, locks up through the upper back contacts and armatures of the relays 217—231, and opens in its upper back contact the circuit of relay 213.

In response to the third interruption of the line-circuit, the relay 201 again releases its armature. The relay 201 closes a circuit from ground through the winding of relay 214, the lower front contact and armature of the relay 215, and the lower back contacts and armatures of the relays 217—231 in series, and the back contact and armature of the relay 201 to grounded battery. The relay 214 becomes energized, locks up through its lower front contact and armature and the lower back contacts and armatures of the relays 216—228 in series. In its lower back contact, the relay 214 opens the locking circuit of the relay 212, and the latter becomes de-energized.

Upon the following closure of the line-circuit, the relay 201 is re-energized, but the relay 202 remains de-energized. The relay 201 causes the energization of relay 217 through a circuit including the upper front contact and armature of relay 214, and the upper back contacts and armatures of the relays 216—228. The relay 217 locks up through the upper back contacts and armatures of the relays 219—231 in series, and opens in its upper back contact the locking circuit of the relay 215, causing the de-energization of the latter.

The fourth or last interruption of the line-circuit results in the de-energization of the relay 201, whereupon the relay 216 is operated through a circuit, including the middle front contact and armature of the relay 217 and the middle back contacts and armatures of the relays 219—231. The relay 216 locks up through its lower front contact and armature and opens the locking circuit of the relay 214.

Upon the re-closure of the line-circuit, the relay 201 becomes energized and closes a circuit for relay 219 through the upper contacts of relays 216-228. The relay 219 becomes energized, locks up and opens the circuit of the relay 217.

This last closure of the line-circuit is of relatively long duration, and the relay 202 has time to attract its armature. A circuit is now closed from ground through the winding of relay 205, the upper back contact and armature of relay 206, the upper front contact and armature of the relay 204, the front contact and armature of the relay 202, and conductor 156 to grounded battery. The relay 205 becomes energized and locks up.

In its lowermost front contact and armature, the relay 205 closes a circuit from ground through the winding of the tens group relay 190, conductor 195, the mentioned contact of relay 205, the upper back contacts and armatures of the relays 209 and 208, and the conductor 156 to grounded battery. The relay 190 becomes energized and closes a circuit from ground through the winding of the fourth tens selecting relay 170, contact 192 of relay 190, conductor 183, the lowermost contact and armature of the relay 219, and conductor 156 to grounded battery. The relay 170 becomes energized and locks up through its contact 171, resistance 175, the back contact and armature of relay 154, and the outer front contact and armature of the relay 114 to grounded battery.

The relay 190 closes another circuit from ground through the relay 208, conductor 193, contact 191 of relay 190, conductor 194 and conductor 156 to grounded battery. The relay 208 becomes energized and closes through its upper front contact and armature, and conductor 156, an energizing circuit for the relay 209. The relay 209 closes a locking circuit for itself through its lower front contact and armature, and conductor 156. Upon the opening of the upper back contact of the relay 208, the locking circuits of the relays 216 and 219 are opened, and these relays become de-energized. Another circuit opened in the upper back contact of the relay 208 is the one including the tens group relay 190, whereupon this relay becomes de-energized. The relay 208 becomes now de-energized, its circuit being opened in contact 191 of the relay 190, but the relay 209 remains locked up.

Units selection.

The relays 201 and 202 being energized, upon the de-energization of the relay 208 the relay 211 becomes energized by current flowing through the above traced circuit. The units digit of the called number is "one," and the calling device is operated to

interrupt the line circuit once and then permanently close it again. Upon the interruption of the line circuit, the relays 201 and 202 become de-energized, and the former closes the above-traced circuit for operating the relay 210, whereupon the latter becomes energized and locks up. The relay 202 closes a circuit from ground through the winding of the relay 206, the lower front contacts and armatures of the relays 205 and 203, the lower back contact and armature of the relay 202, and the conductor 156 to grounded battery. The relay 206 becomes energized and locks up through its middle front contact and armature, and the conductor 156.

Upon the reclosure of the line circuit, the relay 201 and, somewhat later, the relay 202 become energized. The relay 201 causes the energization of the relay 213, and this relay opens the locking circuit of the relay 211. The relay 202 closes a circuit from ground through the winding of relay 207, the upper front contacts and armatures of the relays 206 and 204, the front contact and armature of relay 202 and conductor 156 to grounded battery. The relay 207 becomes energized and locks up through conductor 153. In its lower front contact and armature, the relay 207 connects conductor 153 through conductor 155, the lower armature and front contact of relay 151, and the winding of the units group selecting relay 180 to ground. The relay 180 becomes energized, and closes a circuit from ground through the winding of the first units selecting relay 160, contact 181 of the relay 180, conductor 183^a, the lowermost front contact and armature of the relay 213, and conductor 156 to grounded battery. The relay 160 becomes energized and locks up through its contacts 161, resistance 165, the back contact and armature of the relay 154, and the front contact and armature of the relay 114 to grounded battery.

The first relay 160 and the fourth 170, associated with trunk A, being energized, the selection of the called line No. 41 is completed and this line is connected with the connecting circuit A selected upon the initiation of the call at the station 100. Assuming that the called line is idle, its cut-off relay 107^x is in a de-energized condition and ground potential exists on the test terminal 173 and multiples thereof. For this reason, a marginal test relay 179, associated with trunk A, becomes energized by current flowing from grounded battery through its left-hand high resistance winding, contacts 163 and 173, and the winding of the called cut-off relay 107^x. The cut-off relay 107^x becomes energized in series with relay 179. The relay 179 closes a locking circuit for itself and the cut-off relay of the called line, which circuit includes the right-hand low resistance

winding of the relay 179 and the right-hand inner front contact and armature of the relay 179. Due to the closure of this low resistance path, the potential on the multiples of the test terminal 173 is so changed that no other test relay like 179 can become energized by the current that will flow through its high resistance left-hand winding when shunted by the low resistance winding of the first test relay if another pair of relays like 160 and 170 attempt connection with the called line No. 41.

In its left-hand back contact, the relay 179 opens the energizing circuit of the relay 151, whereupon the latter becomes de-energized and disconnects the counting relays shown in Fig. 2 from the connecting circuit A. Due to the de-energization of this relay, all the relays shown in Fig. 2 that were energized by currents flowing through conductor 158 become de-energized. In its lower front contact and armature, the relay 151 opens the circuit of the relay 180 and this relay becomes de-energized.

A further result of the energization of the relay 179 is the closure of a circuit from ground through the left-hand front contact and armature of the relay 179, the winding of the relay 159, the right-hand back contact and armature of the relay 152; and the right-hand back contact and armature of relay 153 to grounded battery. The relay 159 becomes energized and closes a ringing circuit from ground through a ringing current generator 159^a, the front contact and armature of the relay 159, the right-hand outer front contact and armature of the test relay 179, relay contacts 164 and 174, the bell at the called station, relay contacts 172 and 162, the right-hand middle armature and front contact of the relay 179, and the winding of marginal ringing relay 153 to ground. The called bell is now rung, but due to the relatively high resistance of the bell actuating magnet, the relay 153 does not become energized. When, in response to the ringing of his bell, the called party removes his receiver from the hook, the resistance of the circuit extending through his station is sufficiently reduced to permit the energization of relay 153. In its back contact, the relay 153 opens the circuit of relay 159, and this relay in turn becomes de-energized and opens the ringing circuit. A further result of the energization of the relay 153 is the closure of a circuit from grounded battery through the armature and front contact of relay 153 and the winding of relay 152 to ground. The relay 152 becomes energized and locks up through its left-hand front contact and armature and the front contact and armature of relay 114. The calling and called subscribers may now converse through the circuit indicated in heavy lines, the called party's transmitter being supplied

with current through the retardation coil 158 and the relay 153, and the calling party's transmitter through the retardation coil 150 and the relay 114.

70 *Severing of the connection.*

Upon the termination of the conversation, the calling and called parties hang up their receivers, whereupon the circuits including the relays 114 and 153 are opened and these relays become de-energized. Assuming that the subscribers hang up simultaneously, the relay 114, being slow-to-release, maintains its armatures attracted for a short period of time after the restoration of the armature of the relay 153. For this reason the relay 152 remains locked up for a sufficiently long period of time to permit the closure of a circuit from grounded battery, through the armature and back contact of the relay 153, the right-hand armature and front contact of the relay 152, and the winding of relay 154 to ground. The relay 154 becomes energized and opens in its back contact the locking circuit of relays 160 and 170, whereupon these relays become de-energized. The test relay 179 and the cut-off relay 107^x of the called line become now de-energized.

In the meantime, the relay 114 releases its armatures, with the result that the relays 152, 112, 130, 140 and 107 become de-energized. The relay 152 causes the de-energization of the relay 154. All the apparatus used in the establishment of the connection is now restored to normal and ready for use in the building up of another connection.

If the called subscriber is the first to hang up the receiver, then the severing of the connection proceeds in the same manner as in the above assumed case. If, however, the calling subscriber is the first in restoring his receiver, then the relay 114 releases its armatures while the relay 153 is still energized. The relay 114 causes the de-energization of the above-mentioned relays with the exception of the relay 152, which is maintained energized through the front contact and armature of the relay 153. In its outer front contact and armature, the relay 114 opens the locking circuit of the relays 160 and 170, but these relays are maintained energized through the left-hand front contact and armature of relay 152 and the front contact and armature of the relay 153. When the called party restores his receiver, the relay 153 becomes de-energized and causes the de-energization of the relay 152 and the other relays considered in the first assumed case.

125 *Attempted connection to a busy line.*

If the line leading to station No. 41 is busy as a called line, then the electrical potential on the test terminal 173 is reduced by virtue of the establishment of a low

- resistance path through the right-hand winding of a test relay like 179. If the line leading to this station is busy as a calling line, then the electrical potential on its terminal 173 and multiples thereof is reduced because of the low resistance path closed for its cut-off relay 107* through the contacts of relays like 130 and 140. For either of these reasons, when the relays 160 and 170 become energized, insufficient current flows through the left-hand winding of test relay 179 to permit its energization. The test relay remaining de-energized, the called line is not rung and is maintained severed from the connecting circuit A in the right-hand contacts of relay 179. The relay 151 remains energized and maintains the counting relays (Fig. 2) in their actuated condition. The units group selection relay 180 is also maintained energized. A signaling apparatus, marked "Busy tone," is now inductively connected with the calling line through contacts 182 of relay 180, the upper front contact and armature of the relay 151 and the contacts of relays 140 and 130. The calling subscriber, hearing this busy signal, restores his receiver to the hook, whereupon the relay 114 becomes de-energized and causes the restoration of the actuated apparatus in the above described manner. Upon the de-energization of the relay 112, the relay 151 becomes de-energized and causes in turn the restoration of the relay 180 and the relays shown in Fig. 2. In view of the fact that the relays 152 and 153 are not energized at this stage of the connection (prior to the seizure of the called line), the de-energization of the relay 114 results also in the de-energization of the relays 160 and 170.
- From the foregoing, it will be seen that the connector relays 160 and 170 are operated irrespective of the busy or idle condition of the called line, and are maintained operated until the calling party restores the receiver to the switch-hook. If, therefore, the calling subscriber chooses to wait until the called line becomes idle, he will maintain the mentioned connection to the called line, but will be unable to intrude upon the connection already existing with the called line, because his connection is maintained open in the right-hand front contacts of relay 179. As soon as the called line becomes idle, the relay 179 becomes energized and causes the completion of the connection in the above described manner.
- 60 *Connection of calling private branch exchange line to city line.*
- If the subscriber at the station 100 desires connection with an outside subscriber, such as B (Fig. 4), he initiates a call in the same manner as in the case of a local or private branch exchange connection. His line is connected with the trunk A and the associated counting relays. In order to obtain a city connection, the subscriber operates his calling device to send a group of 70 ten impulses to the counting relays. The counting relays operate in the above described manner.
- In response to the tenth interruption of the line circuit by the sending device, the 75 counting relay 228 becomes energized and locks up. The energization of this relay results in the establishment of a path from grounded battery through the outer armature and front contact of the relay 114, 80 the middle armature and front contact of the relay 151, conductor 156, the lowermost front contact and armature of the relay 231, the lowermost armature and back contact of the relay 206, conductor 115, 85 the winding of relay 113, and the right-hand back contact and armature of the relay 110 to ground. The relay 113 becomes energized.
- In its middle back contact, the relay 113 90 opens the circuit, including relays 114, and in its outer right-hand back contacts, the circuit of relays 112, 130, 140, and 107. These relays become de-energized and restore the connection between the calling 95 line and the trunk A. The de-energization of the relay 112 results in the de-energization of the relay 151 and the subsequent disconnection of the counting relays.
- Prior to the restoration of the counting 100 relays, the last long impulse causes the actuation of the relay 202, but due to the retarded energization of this relay, the relay 113 has time to become energized, and being itself slow-to-release its armatures, 105 performs further functions to be presently described. Furthermore, under the joint control of the relays 231, 202 and 205, the relay 190 and the tenth relay 170 are energized in the above described manner. However, upon the de-energization of the relay 114, all the actuated counting relays and the relays 190 and 170 are de-energized. 110
- The further functions performed by the relay 113 are as follows: In its left-hand armature and front contact, this relay closes a circuit through the left-hand armature and back contact of the relay 110, and the winding of relay 111 to ground. The relay 111 becomes energized. Another circuit, closed by relay 113, extends from ground through its right-hand inner armature and front contact, the armature and back contact of relay 302, and the winding of relay 350 to grounded battery. The relay 350 becomes energized. The relay 350 closes circuits from ground through the winding of relay 302, the windings of relays 370 and 360, representing the calling line number, relay contacts 351 and 352, and 120

the right-hand front contacts and armatures of the relay 109 to grounded battery. The relays 302, 360 and 370 become energized. These relays are locked up through a circuit including the relay contacts 361, 371, resistances 369, 379, and the left-hand armature and back contact of relay 309 to grounded battery.

If the city trunk with which the relay 302 is associated is busy, then the ground from the right-hand middle armature and front contact of the relay 113 is extended through the armature and front contact of the relay 302, and through the armatures and front contacts of all the relays 302 associated with busy city trunks, to the armature and back contact of an idle relay, e.g. 302ⁿ, and then through the winding of the associated selecting relay 350ⁿ to grounded battery. This relay operates like the relay 350 to cause the extension of the calling line to the city trunk represented by it.

As above stated in connection with the description of the operations performed in extending the calling line to trunk A, upon the initiation of a call and until the line is connected with the trunk, the relay 110 is energized. While this relay is energized, it maintains open in its right-hand back contact the circuit of relay 113, preventing a false operation of the latter. For the relatively short period of time that the relay 113 is energized, the relay 111 is maintained energized and prevents the energization of relay 110 and the subsequent premature de-energization of relay 113 in response to the initiation of another call. The extension of a calling line during this period of time is delayed until the relay 113 becomes de-energized.

Another circuit closed by relay 350 is from ground through the contacts 353 of this relay and the winding of relay 301 to grounded battery. The relay 301 becomes energized and closes a locking circuit for itself through its inner front contact and armature and the right-hand back contact and armature of relay 309. Upon the energization of the relay 302, the relay 350 becomes de-energized. Shortly after this, the relay 113 releases its armatures, and causes in turn the de-energization of relay 111.

In response to the operation of the relays 360 and 370, a circuit is closed from ground through the winding of relay 107, relay contacts 363 and 373, the high resistance right-hand winding of test relay 303, to grounded battery. The relays 107 and 303 become energized, and the relay 303 closes a locking circuit for these relays through its low resistance left-hand winding and left-hand armature and front contact. Due to the closure of this low resistance path, the calling line is rendered busy as above described.

A further result of the energization of the

relays 360 and 370 is the establishment of a circuit from ground through the winding of relay 311, the upper armature and back contact of relay 304, relay contacts 374 and 364, the loop through the calling station, relay contacts 362 and 372, the winding of slow acting relay 306, the outer left-hand armature of relay 303 to grounded battery. The relays 306 and 311 become energized, and the former closes a circuit through its left-hand armature and front contact for energizing relay 307. The relay 307 locks up through its left-hand inner front contact and armature and the left-hand back contact and armature of the relay 309.

The calling private branch exchange line is now extended to an answering jack 400, located at the city exchange operator's position. A circuit is closed from grounded battery through the winding of relay 402, the upper back contact and armature of relay 403, conductor 321, the winding of relay 323, the right-hand front contact and armature of relay 303, conductor 322, and the lower armature and back contact of relay 403 to ground. The relays 323 and 402 become energized. The relay 402 causes the lighting of lamp 410, whereupon the city operator inserts an answering plug 401 into the answering jack 400. The relay 403 becomes energized and causes the de-energization of relay 402. The relay 323 remains energized by current supplied through the repeating coil of the city operator's cord circuit.

The city operator converses with the private branch exchange subscriber in the well-known manner, and completes the connection to the called line through calling plug 405 and multiple jack 406. The ringing of the called station by closure of the ringing key 420 and the operation of the supervisory apparatus at the city operator's position is accomplished in the well-known manner.

If at any time during conversation, the private branch operator wants to talk with either one of the subscribers, she may do so by connecting her telephone set 355 in bridge of the conductors 321, 322 through the contacts of 324.

If the operator desires to talk with the private branch exchange subscriber to the exclusion of the city subscriber or operator, she actuates key contacts 325. Through the lower contacts of 325 an energizing circuit is closed for relay 312. This relay becomes energized, opens the city side of the connection, and connects the operator's telephone set through the upper and middle make contacts of 325, and conductors 321 and 322 with the private branch exchange subscriber's telephone. In response to the restoration of the contacts 325, the circuit is restored to its talking condition.

The private branch exchange subscriber

may call the branch exchange operator, if he so desires, by moving his switch-hook up and down or by operating his dial. This interrupts momentarily the energizing circuit of relays 311 and 306, as described above. The slow-acting relay 306 does not release its armatures, but relay 311 responds to the interruptions of the circuit. A circuit is closed from ground through the armature and back contact of relay 311, winding of relay 308, outer left-hand armature and front contact of relay 307, to grounded battery at the contacts of key 325. The relay 308 is energized and locks up through its inner armature and front contact. The relay 308 closes a circuit from battery, contacts of key 325, outer armature and front contact of relay 308, call lamp 330, front contact and inner armature of relay 308 to ground. The lamp 330 is lighted, indicating to the private branch exchange operator that a party using the trunk associated with the call lamp desires to converse with her. By means of key 324, she connects here telephone set 355 to conductors 321, 322, as above described. When disconnection is desired and the calling party restores his receiver to the switch hook, the relays 311 and 306 become de-energized. The relay 306 closes a circuit from grounded battery through its left-hand armature and back contact, the right-hand armature and front contact of relay 307 and the slow acting relay 309 to ground. The relay 309 opens its back contacts, whereupon the relays 301, 302, 307, 360 and 370 become de-energized. Upon the de-energization of relay 307, the relays 308 and 309 become de-energized, and upon the de-energization of relays 360 and 370 the relays 107 and 303 become de-energized.

The city operator receives the clearing-out signal in the well-known manner, and restores the calling side of the connection.

45 *Extension of call from city exchange to private branch exchange substation.*

The subscriber at station B, desiring a connection, causes the lighting of lamp 411, whereupon the city operator extends his line through jack 407, plug 401, plug 405 and jack 401 to conductors 321, 322. The city operator actuates her ringing key 420, and the alternating current relay 323, bridged across these trunk conductors responds to the ringing current, and connects grounded battery through the left-hand outer armature and back contact of relay 303, the armature and front contact of the relay 323, and the winding of slow acting relay 312 to ground. The relay 312 becomes energized and closes a circuit from grounded battery through its lower armature and front contact, the lamp 330, and the back contact and armature of the relay 311 to

ground. The lamp 330 is lighted, and the operator at the private branch exchange makes her inquiry in the above described manner by connecting her telephone set 355 to the trunk conductors 321, 322, through the key contacts 324. When the flow of ringing current ceases, the relay 323 and, in turn, relay 312 become de-energized.

The private branch exchange operator actuates now key 333, indicating the group of the called subscriber, and the keys 340 and 341, indicating the tens and units digits, respectively, of the called number. Due to the actuation of these keys, the following circuits are closed; from ground through the winding of the relay 380, the upper contact of key 333, and the left-hand contact of key 341 to grounded battery. The relay 380 becomes energized and closes the following circuits; from ground through the winding of slow acting relay 302, and then in parallel through the winding of relays 370 and 360, relay contacts 381 and 382, and the contacts of keys 340 and 341 to grounded battery. The relays 302, 360 and 370 become energized, and lock up through resistance 369 and 379 to grounded battery at the left-hand armature of the relay 309.

Assuming that the line is idle, the marginal test relay 303 pulls up through its high resistance right-hand winding, and locks up through its low resistance left-hand winding, protecting the line against seizure. A circuit is now closed from ground, through the outer armature and back contact of the relay 301, the right-hand armature and front contact of the relay 303, the winding of relay 304, the back contact and armature of the relay 310, and the back contacts and armatures of the relays 307 and 306 to grounded battery. The relay 304 closes a circuit from grounded battery through its lower armature and front contact, the winding of relay 305 to ground, and the lamp 331 to ground. The relay 305 completes the ringing circuit which may be traced from ground through the ringing current generator 320, the upper front contact of the relay 304, relay contacts 364 and 374, the bell at the called station, relay contacts 362 and 372, the lower armature and front contact of the relay 305, and the winding of marginal ringing relay 310 to grounded battery. The lighting of lamp 331 indicates to the operator that the called line is being rung. Through its middle armature and front contact, the relay 304 bridges the relay 323 across the trunk conductors 321, 322. The relay 323 becomes energized.

When, in response to the ringing of his bell, the called subscriber removes the receiver from the hook, the resistance of the last traced circuit is sufficiently reduced to permit the energization of relay 310. The relay 304 becomes de-energized now and

permits the de-energization of the relay 305 and the extinguishing of the lamp 381. During ringing, a tone is sent to the calling party through the follow-up contacts of the relay 304, resistance 356, and the upper front contact and armature of the relay 305. Upon the de-energization of the relay 305, the relay 310 becomes de-energized, but the relay 304 cannot be re-energized because, as

- 10 a further result of the de-energization of the relay 304, a circuit is closed through the called line circuit and the windings of relays 311 and 306. These relays become energized and the latter causes the energization and locking up of the relay 307, and opens the circuit of relay 304. Instead of the path including the contacts of relay 304, the relay 323 is now bridged across the trunk conductors through the right-hand contacts of 15 relay 306. The calling and called parties may converse through the conductors indicated in heavy lines.

The restoration to normal of the relays is accomplished in the above described manner.

- 20 *Attempted connection to a busy private branch exchange line.*

If the called private branch exchange subscriber is busy, then the marginal test relay 303 does not become energized upon the operation of the relays 360 and 370. For this reason the relay 304 cannot become energized to cause the ringing of the called station. A circuit is also closed from ground 25 through the outer armature and back contact of the relay 301, the right-hand armature and back contact of relay 303, the lower make contacts of 333, lamp 384, and the left-hand contacts of 341 to grounded battery. The lamp 384 is lighted to inform the operator of the busy condition of the called line. By means of her telephone set 355 the operator informs the city operator or the calling party of the busy condition of the 40 called line. Then she actuates key contacts 332 to restore the relays to their normal condition.

In case it is desired to maintain the city connection with the called private branch exchange line until the latter becomes idle, the city subscriber cannot overhear the conversation because the trunk conductors 321 and 322 are maintained open through the agency of relay 312. The latter is maintained energized through listening key contacts 325 or through a circuit including the armature and front contact of relay 323 and the left-hand outer armature and back contact of relay 303. As soon as the called line 45 becomes idle, the relay 312 is de-energized by the opening of its circuit in the back contact of relay 303 or in the contacts of 325.

As above stated, the private branch exchange operator is apprised of the busy condition of the private branch exchange line

through the agency of lamp 384. The city operator is also signaled in such case, because, due to the inactive condition of relays 306 and 304, the calling supervisory relay 414 does not extinguish the lamp 415. Both operators being informed of the busy condition of the line, either one or both may cause the holding of the connection. As soon as the called line is seized, both lamps are extinguished.

75 What I claim is:—

1. In a telephone exchange system, a plurality of lines, a variably operable impulse sending device associated with each line, a plurality of sets of counting relays, a plurality of trunks, a plurality of line switching relays provided with contacts appertaining to said lines, means for actuating said relays to select a trunk and to connect a calling line with one end of the selected trunk, a relay 80 associated with each trunk, a set of counting relays associated with the relay of the selected trunk, means common to said lines for operating the relay associated with the selected trunk to connect said set of counting relays to 85 said trunk, a controlling circuit between the impulse sending device of the calling line and the counting relays associated with the selected trunk, contacts of the relay associated with the selected trunk, in said controlling circuit, another plurality of line switching relays provided with contacts appertaining to said lines, actuating means for the last mentioned switching relays, controlling circuits between said set of counting relays and the actuating means of all of said last mentioned switching relays whereby 90 said trunk may be connected to the called line, and means responsive to the actuation of the contacts of one of the last mentioned 95 switching relays for actuating the relay associated with the selected trunk.

100 2. In a telephone exchange system, a plurality of lines, means including a switch for interconnecting said lines, means for rendering busy said lines, a numerical register, means for operatively associating said register with said switching means, means whereby said switching means is selectively operated in accordance with the adjustment 105 of said register, and means operable depending on the busy or idle condition of called lines, for controlling said associating means.

110 3. In a telephone exchange system, a plurality of lines, means including a switch for establishing a connecting circuit between said lines, means for rendering busy said lines, switch controlling mechanism, connecting means for associating said mechanism with said circuit, means whereby said 115 switching means is selectively operated in accordance with the adjustment of said controlling mechanism, and means responsive to the idle or busy condition of called lines for controlling said connecting means.

4. In a telephone exchange system, a plurality of lines, means including a switch for establishing a connecting circuit between said lines, switch controlling mechanisms, 5 means operative upon the initiation of the establishment of said circuit for connecting said mechanisms with the circuit, means for rendering said lines busy, means whereby said switching means is selectively operated 10 in accordance with the adjustment of said controlling mechanisms, means operable upon the establishment of said circuit in connection with an idle line for disassociating said mechanisms from the circuit, and 15 means responsive to the busy condition of lines for maintaining said mechanisms in association with said circuit.
5. In a telephone exchange system, a plurality of lines, a switching device for selecting one of said lines, means for rendering busy said lines, testing means responsive to the busy or idle condition of said lines associated with said device, controlling means 20 for said device, means whereby said switching device is selectively operated in accordance with the adjustment of said controlling means, means for controlling the operative association between said controlling means and said device, and means controlled by 25 said testing means for operating said last mentioned means.
6. In a telephone exchange system, a plurality of lines, means for rendering busy said lines, a switching device for selecting 30 one of said lines, testing means associated with the said switching device, signalling means associated with said device, controlling means for said device, means for associating said controlling means with said device, means responsive to the operation of the said testing means for operating said last mentioned means, and means responsive to the operation of the testing means for operating the said signalling means.
7. In a telephone exchange system, a plurality of lines, a variably operable impulse sending device associated with each line, a plurality of sets of counting relays, a plurality of line switching relays, a plurality 40 of connecting relays, means common to said lines for operating one of said connecting relays for operatively associating a certain set of counting relays with said switching relays, means controlled by the impulse sending device of the calling line for adjusting the counting relays in accordance with the numerical designation of the called line, means for rendering busy said lines, a test relay, means controlled by said set of counting 45 relays for operating said switching relays to select and seize the called line, a circuit for operating the test relay depending on the idle or busy condition of the called line, and a circuit for said one of the said connecting relays controlled by said test relay.
8. In a telephone exchange system, a plurality of lines, means for rendering busy said lines, a selectively operable switching device, a controlling means for said device, a busy signaling apparatus, and a relay effective to control the association of said controlling means with said switching device and to render operative said apparatus. 70
9. In a telephone exchange system, a plurality of lines, a plurality of "tens" and "units" line selecting relays, a switching relay common to said "tens" relays and a switching relay common to said "units" relays, a variably operable controlling means for said switching and selecting relays, means for rendering busy said lines, testing means and a busy tone apparatus associated with said selecting relays, and means under the joint control of the switching relay common to the "units" selecting relays and the said testing means for connecting the busy tone apparatus with the calling line. 75
10. In a telephone exchange system, a calling and a called line, means including a selectively operable switching device for interconnecting said lines, means for rendering busy said called line, testing means associated with said device, a busy signaling apparatus, a controlling means for said switching device, a relay provided with contacts appertaining to said lines, apparatus, switching device, and controlling means, and means for actuating said relay to connect said controlling means to said device and said apparatus with the said calling line. 80
11. In a telephone exchange system, a calling and a called line, means including a selectively operable switching device for interconnecting said lines, means for rendering busy said called line, a controlling means for said switching device, testing means associated with said device, a busy signaling apparatus, a relay operative to connect said controlling means with said device, and means under the joint control of the said relay and said device for associating said apparatus with the calling line. 85
12. In a telephone exchange system, calling and called lines, means for producing current impulses representing digits of called line numbers, a switch, means for operating said switch in accordance with impulses representing digits of said numbers for connecting with called lines, another switch for extending a calling line to said switch, restoring means for said switches, and means responsive to the production of the impulses representing a particular digit for restoring said last mentioned switch before the first switch has been operated to extend the connection to the called line. 110
13. In a telephone exchange system, calling and called lines, means for producing 120
- 125
- 130

current impulses representing digits of called line numbers, a plurality of line switching relays, means for operating said relays in accordance with impulses representing two of said digits for connecting with a called line, means including another line switching relay for extending a calling line to an idle one of said first mentioned relays, restoring means for said relays, and means responsive to the production of the impulses representing one of said two digits for restoring said last mentioned relay.

14. In a telephone exchange system, a calling line, called lines, switching means for interconnecting said calling line and certain of said called lines, other switching means, means for actuating said switching means upon the initiation of a call from said calling line and for maintaining said switching means actuated if the called line is any one of said certain lines, and means for restoring said switching means if the called line is another of said lines and for extending the connection through said other switching means.

15. In a telephone exchange system, a plurality of lines, means for producing current impulses representing digits of called line numbers, an electromagnetic switch operable in accordance with said impulses to select a called line, another electromagnetic switch, automatic means for operating said other switch to connect a calling line with said first mentioned switch in response to the initiation of a call, holding circuits for said switches, and a slow acting relay having contacts in said circuits.

16. In a telephone exchange system, a plurality of lines leading to subscribers' stations, a line switching relay for interconnecting said lines, an actuating and a holding circuit for said relay, a first relay common to said lines, a contact of the first relay in the holding circuit, a second relay common to said lines, a contact of said second relay in the holding circuit, a circuit for said first relay, and a contact of said second relay and a contact at the substation in said last mentioned circuit.

17. In a telephone exchange system, a plurality of lines leading to subscribers' stations, a line switching relay for interconnecting said lines, an actuating and a holding circuit for said relay, a first slow-acting relay common to said lines, a contact of the first relay in the holding circuit, a second slow-acting relay common to said lines, a contact of said second relay in the holding circuit, a circuit for said first relay, and a contact of said second relay and a contact at the substation in said last mentioned circuit.

18. In a telephone exchange system, a calling and called lines, a switch for interconnecting said lines, a relay for controlling the

restoration of said switch, a circuit for said relay including three contacts, means associated with said switch for controlling one of said contacts, means associated with and individual to the calling line for controlling another contact, and means common to a plurality of said lines for controlling the third contact.

19. In a telephone exchange system, calling and called lines, a switch, contacts for said switch for interconnecting said lines, a slow-acting relay for controlling the restoration of said switch, a circuit for said relay including the calling line conductors and two contacts and one of said contacts of the switch, means at the calling station for controlling one of said two contacts, and means common to a plurality of said lines for controlling the other one of said two contacts.

20. In a telephone exchange system, a plurality of lines, a circuit, means for producing in said circuit current impulses representing digits of called line numbers, a slow acting relay in said circuit, a switch operable in accordance with said impulses for selecting a called line, another switch for connecting a calling line with said switch, a holding circuit for each switch, and contacts of said slow acting relay in said holding circuits.

21. In a telephone exchange system, a plurality of lines, a circuit, means for producing in said circuit current impulses representing digits of called line numbers, a slow and a quick acting relay in said circuit, counting relays responsive to said impulses, a line switching relay controlled by said counting relays to select a called line, another line switching relay for connecting a calling line with said switching relay, a holding circuit for each relay, another circuit including said current impulse producing means, a slow relay in said other circuit and contacts for said last mentioned slow acting relay in said holding circuits.

22. In a telephone exchange system, a plurality of telephone lines, a plurality of connecting circuits, a plurality of relay switching devices, actuating means for each of said devices, means operable over one of said lines for actuating one of said devices, a set of counting relays at the exchange, means controlled by said counting relays for actuating another one of said devices, contacts on said devices appertaining to said lines, and contacts on said devices appertaining to said connecting circuits.

23. In a telephone exchange system, a plurality of incoming and outgoing lines, a relay for each ten incoming lines, a relay for each ten outgoing lines, a group of ten relays for incoming lines, another group of ten relays for outgoing lines, means responsive to the initiation of a call over an incoming line for actuating the relay of the

- group of ten incoming lines including the calling line, simultaneously operating means for actuating a certain one of said first mentioned group of ten relays, means including a numerical register controlled over the incoming line for actuating any one of the relays appertaining to groups of ten outgoing lines and any one of the second group of ten relays, and a connecting circuit between the calling incoming line and an outgoing line including contacts of actuated relays.
24. In combination, a circuit, an interrupting device at one end of said circuit, a controlling relay at the other end of said circuit responsive to said device, contacts for said relay, two groups of relays having contacts, actuating circuits for the relays of one group through one contact of said controlling relay, the contacts of active and inactive relays of the second group, and actuating circuits for the relays of the second group through another contact of the controlling relay and contacts of active and inactive relays of said one of said groups.
25. In combination, a circuit, an interrupting device at one end of said circuit, a controlling relay at the other end of said circuit responsive to all operations of said device, a front and a back contact for said relay, two groups of serially arranged relays having front and back contacts, successive actuating circuits closed for the relays of one group through the front contact of said controlling relay, the back contacts of inactive and the front contact of an active relay of the second group, locking circuits for the relays of the said first mentioned group through the front contact of the actuated relay and the back contacts of other relays of said first mentioned group, successive actuating circuits for the relays of said second group through the back contact of the controlling relay, the front contact of an active and the back contacts of the inactive relays of said first mentioned group, and locking circuits for the relays of said second group through the front contact of the actuated relay and the back contacts of the inactive relays of the said second group.
26. In combination, a circuit, an interrupting device at one end of said circuit, a controlling relay at the other end of said circuit responsive to said device, a front and a back contact for said relay, two groups of serially arranged relays having front and back contacts, successive actuating circuits closed for the relays of one group through the front contact of the controlling relay, the front contact of an active relay of the second group, locking circuits for the relays of the said first mentioned group through the front contact of the actuated relay and the back contacts of the inactive relays of said first mentioned group, successive actuating circuits for the relays of said second group through the back contact of the controlling relay, the front contact of an active and the back contacts of the inactive relays of said first mentioned group, locking circuits for the relays of the second group through the front contact of the actuated relay and the back contacts of the inactive relays of the said second group.
27. In combination, a circuit, an interrupting device at one end of said circuit, a controlling relay at the other end of said circuit responsive to said device, a front and a back contact for said relay, two groups of serially arranged relays having front and back contacts, successive actuating circuits closed for the relays of one group through the front contact of said controlling relay, the back contacts of inactive and the front contact of an active relay of the second group, locking circuits for the relays of the said first mentioned group through the front contact of the actuated relay and the back contacts of the other relays of said first mentioned group, successive actuating circuits for the relays of the second group through the back contact of the controlling relay, the front contact of an active and the back contacts of the inactive relays of said first mentioned group, locking circuits for the relays of the second group through the front contact of the actuated relay and the back contacts of the inactive relays of the said second group, a slow-acting relay in a branch of said first mentioned circuit, and a contact controlled by said last mentioned relay in said locking circuits.
28. In combination, a circuit, an interrupting device at one end of said circuit, a controlling relay at the other end of said circuit responsive to said device, a front and a back contact for said relay, two groups of serially arranged relays having front and back contacts, successive actuating circuits closed for the relays of one group through the front contact of said controlling relay, the back contacts of inactive and the front contact of an active relay of the second group, locking circuits for the relays of the said first mentioned group through the front contact of the energized relay and the back contacts of the other relays of said first mentioned group, successive actuating circuits for the relays of the second group through the back contact of the controlling relay, the front contact of an active and the back contacts of the inactive relays of said first mentioned group, locking circuits for the relays of the second group through the front contact of the actuated relay and the back contacts of the inactive relays of the said second group.

said second group, other contacts in said locking circuits, and means controlled by the relays of one of the groups for actuating said contacts.

5 29. In combination, a circuit, an interrupting device at one end of said circuit, a controlling relay at the other end of said circuit responsive to certain operations of said device, two contacts for said relay, two 10 groups of relays, actuating circuits for the relays of one group through one contact of the controlling relay and contacts of an active and inactive relays of the other group, and actuating circuits for the relays of the 15 other groups through the other contact of the controlling relay and contacts of an active and inactive relays of said one group.

30. In combination, a circuit, an interrupting device at one end of said circuit, a controlling relay at the other end of said circuit, a front and a back contact for said relay, two groups of serially arranged relays, successive actuating circuits for the relays of one group through the front contact 20 of the controlling relay, the back contacts of inactive relays and the front contact of an active relay of the second group, a locking circuit for the relays of said one group, successive actuating circuits for the relays 25 of said second group through the back contact of the controlling relay, the front contact of an active relay and the back contacts of inactive relays of said one group, and a locking circuit for the relays of said 30 second group.

31. In combination, a slow acting controlling relay, a second controlling relay, an interrupting device in circuit with said relays, said slow relay responding only to certain operations of said interrupting device, 35 two groups of serially arranged relays, successive actuating circuits for the relays of one group through a contact of the second controlling relay, the contact of an inactive relay and the contact of an active relay of the second group, successive actuating circuits for the relays of the second group through another contact of said second controlling relay, the contact of an inactive relay and the contact of an active relay of 40 said one group, locking circuits for the relays of said groups, and a contact on said slow acting controlling relay common to said locking circuits.

55 32. In combination, a group of n relays provided with contacts, a second group of n^1 relays provided with contacts, the energizing circuit of the first relay of the first group being connected to a back contact of 60 the first relay of said second group, the respective energizing circuits of the remaining relays of the first group being connected in order to front contacts of the relays of said second group, and the respective energizing circuits of the relays of said second

group being connected in order to front contacts of the first n^1 relays of the first group.

33. In combination, a circuit, an interrupting device arranged to produce impulses at one end of said circuit, a first controlling relay 70 and a second controlling relay responsive to impulses at the other end of the circuit, a first, a second, a third and a fourth group of relays, contacts for all of said relays, actuating circuits for the relays of 75 the first group through a contact of the first controlling relay and contacts of inactive and active relays of the second group, actuating circuits for the relays of the second group through another contact of the 80 first controlling relay and contacts of inactive and active relays of the first group, actuating circuits for the relays of the third group through a contact of the second controlling relay and contacts of inactive and 85 active relays of the fourth group, and actuating circuits for the relays in the fourth group through another contact of the second controlling relay and contacts of inactive and active relays of the third group. 90

34. In combination, a circuit, an interrupting device arranged to produce impulses of short and long duration at one end of said circuit, a first controlling relay responsive to all impulses and a second controlling relay 95 responsive only to the long impulses at the other end of the circuit, a branch for said circuit including a slow-to-release relay, a first, a second, a third and a fourth group of serially arranged relays, contacts 100 for all of said relays, actuating circuits for the relays of the first group through the front contact of the first controlling relay, the back contacts of the inactive and the front contact of an active relay of the second group, locking circuits for the relays of the first group through the front contact of an active and the back contacts of the inactive relays of the first group and the front contact of the slow-to-release relay, 105 actuating circuits for the relays of the second group through the back contact of the first controlling relay, the back contacts of inactive and the front contact of an active relay of the first group, locking 110 circuits for the relays of the second group through the front contact of an active, the back contacts of inactive relays of the second group and the front contact of the slow-to-release relay, actuating circuits for the relays of the second group through the back contact of the first controlling relay, the back contacts of inactive and the front contact of an active relay of the first group, locking 115 circuits for the relays of the second group through the front contact of an active, the back contacts of inactive relays of the second group and the front contact of the slow-to-release relay, actuating circuits for the relays of the second group through the back contact of the first controlling relay, the back contacts of inactive and the front contact of an active relay of the first group, locking 120 circuits for the relays of the second group through the front contact of an active, the back contacts of inactive relays of the second group and the front contact of the slow-to-release relay, actuating circuits for the relays of the second group through the back contact of the first controlling relay, the back contacts of inactive and the front contact of an active relay of the first group, locking 125 circuits for the relays of the second group through the front contact of an active, the back contacts of inactive relays of the second group and the front contact of the slow-to-release relay, actuating circuits for the relays of the second group through the back contact of the first controlling relay, the back contacts of inactive and the front contact of an active relay of the first group, locking 130 circuits for the relays of the second group through the front contact of an active, the back contacts of inactive relays of the second group and the front contact of the slow-to-release relay.

through the front contact of the said slow-to-release relay, another relay having contacts in the locking circuits of the relays of the first and second groups, and means controlled by a relay in the third group for actuating said other relay.

35. In combination, a circuit, an interrupting device arranged to produce impulses of short and long duration at one end of said circuit, a first controlling relay responsive to all impulses and a second controlling relay responsive only to the long impulses at the other end of the circuit, a branch for said circuit, including a slow-to-release relay, a first, a second, a third and a fourth group of serially arranged relays, contacts for all of said relays, actuating circuits for the relays of the first group through the front contact of the first controlling relay, the back contacts of the inactive and the front contact of an active relay of the second group, locking circuits for the relays of the first group through the front contact of an active and the back contacts of the inactive relays of the first group and the front contact of the slow-to-release relay, actuating circuits for the relays of the second group through the back contact of the first controlling relay, the back contacts of inactive and the front contact of an active relay of the first group, locking circuits for the relays of the second group through the front contact of an active, the back contacts of inactive relays of the second group, and the front contact of the slow-to-release relay, actuating circuits for the relays of the third group through the front contact of the second controlling relay, the back contacts of inactive and the front contacts of active relays of the fourth group, actuating circuits for the relays in the fourth group through back contacts of inactive and front contacts of active relays of the third group, locking circuits for the relays of the third and fourth groups through the front contact of the said slow-to-release relay, and means controlled by a relay in the fourth group for actuating said slow-to-release relay.

36. In combination, a circuit, an interrupting device arranged to produce impulses of short and long duration at one end of said circuit, a first controlling relay responsive to all impulses and a second controlling relay responsive only to the long impulses at the other end of the circuit, a branch for said circuit including a slow-to-release relay, a first, a second, a third and a fourth group of serially arranged relays, contacts for all of said relays, actuating circuits for the relays of the first group through the front contact of the first controlling relay, the back contacts of the inactive and the front contact of an active relay of the second group, locking circuits for the relays of the first group through the front contact of an active and

the back contacts of the inactive relays of the first group and the front contact of the slow-to-release relay, actuating circuits for the relays of the second group through the back contact of the first controlling relay, 70 the back contacts of inactive and the front contact of an active relay of the first group, locking circuits for the relays of the second group through the front contact of an active, the back contacts of inactive relays of the second group and the front contact of the slow-to-release relay, actuating circuits for the relays of the third group through the front contact of the second controlling relay, the back contacts of inactive and the front contacts of active relays of the fourth group, actuating circuits for the relays in the fourth group through the back contact of the second controlling relay, back contacts of inactive and front contacts of active relays of the third group, locking circuits for the relays of the third and fourth groups through the front contact of the said slow to release relay, another relay having contacts in the locking circuits of the relays of the first and second groups, and means under the joint control of a relay in the third group and a relay in the first group for actuating said other relay.

37. In a telephone exchange system, a calling telephone line, a plurality of trunk lines, a pair of relays provided with contacts through which said telephone line is extended to a trunk line, means responsive to the initiation of the call for actuating said pair 95 of relays, another pair of relays provided with contacts through which said telephone line is extended to a certain one of said trunk lines, means operable over said calling line for actuating said other pair of relays, 100 and selectively operable means for actuating said other pair of relays.

38. In a telephone exchange system, two groups of lines, means for rendering busy said lines, a switch, means for operating said switch to connect a certain calling line of one group with an idle called line of the other group, means for operating said switch to connect a certain calling line of the said other group with a certain called 110 line of the said one group, a source of ringing current, a relay operable in response to the actuation of said switch for controlling the connection of said source with called lines, and means for preventing the operation of said relay in response to the first mentioned operation of the switch.

39. In a telephone exchange system, a two-way trunk, a manual switching device at one end of said trunk, and a digital set of tens and units relays containing multipled terminals of the other end of said trunk.

40. In a telephone exchange system, a two-way trunk, a switching device at one end of said trunk, a subscriber's line, a relay com- 130

prising answering terminals of said line, and contacts in said relay forming terminals of the other end of said trunk.

41. In a telephone exchange system, a subscriber's line, a two-way trunk, switching means comprising a plurality of relays each having contacts in the talking circuit between said line and trunk, and means for actuating said switching means to connect 10 said line either as a calling or as a called line with said trunk.

42. In a telephone exchange system, subscriber's lines, a two-way trunk, a plurality of relays provided with contacts in the talking circuit between said lines and trunk, automatic means operable in response to a call over one of said lines to selectively operate certain of said relays to connect said line to said trunk, and directly controlled means 20 to selectively operate said certain of said relays to connect said line as a called line to said trunk.

43. In a telephone exchange system, a subscriber's line, a two-way trunk, a plurality of relays provided with contacts in the talking circuit between said lines and trunk, controlling means associated with said trunk, means under the control of the subscriber for selectively actuating certain of said 30 relays to connect his line to said trunk, and other means including said controlling means for selectively actuating said certain of said relays to connect said line and trunk.

44. In a telephone exchange system, a subscriber's line, a two-way trunk, an operator's position associated with said trunk, a plurality of switching relays provided with contacts in the talking circuit between said lines and trunk, means operable over said 40 line for selectively actuating certain of said relays to connect said line to said trunk, and means under the control of the operator for selectively actuating said certain of said relays to connect said line to said trunk.

45. In a telephone exchange system, a calling line and two called lines, a switch, means responsive to the initiation of a call toward one of said called lines for actuating said switch, a connecting circuit between 50 said calling line and said one of said called lines including said switch, another switch, means responsive to the initiation of a call toward the other called line for actuating both said switches, and a connecting circuit between said calling line and said other called line including only said other switch.

46. In a telephone exchange system, a calling line and two called lines, a line-switching relay, means responsive to the initiation of a call toward one of said called lines for actuating said relay, a connecting circuit between said calling line and said one of said called lines including contacts of said relay, another switching relay, means 60 responsive to the initiation of a call toward

the other called line for actuating both said relays, and a connecting circuit between said calling line and said other called line including only contacts of said other switching relay.

47. In a telephone exchange system, calling and called lines, two switches having actuating and restoring means, means responsive to the initiation of a call for operating the actuating means of one switch to extend 70 the calling line toward the called line, means controllable over the calling line for actuating the restoring means of said switches, means operable over said calling line for operating the actuating means of the other 75 switch, and means responsive to the operation of the said last mentioned means for operating the restoring means of the said one switch.

48. In a telephone exchange system, a calling line and two called lines, a switch, actuating and restoring means for said switch, means responsive to the initiation of each call on said calling line for actuating said switch to extend the calling line toward a 80 called line, another switch, means operative upon the extension of calls toward a certain one of said called lines for actuating said other switch, and means operative thereupon 85 for actuating said restoring means.

49. In a telephone exchange system, a calling line and two called lines, a line-switch, actuating and restoring means for said switch, means responsive to the initiation of each call on said calling line for actuating 90 said line-switch to extend the calling line toward a called line, another line-switch, means operative upon the extension of calls toward a certain one of said called lines for actuating said other switch, and means operative 95 thereupon for actuating said restoring means.

50. In a telephone exchange system, a plurality of subscribers' lines, means including a line-switching relay for interconnecting 100 said lines, a holding circuit for said relay, a contact in said circuit, subscriber controlled means for actuating said contact, and separate automatically controlled means for actuating said contact.

51. In a telephone exchange system, calling and called subscribers' lines, means including a switch for connecting a calling line with a called line, actuating and restoring means for said switch, means responsive to the initiation of a call for operating 110 said actuating means, manually operable means associated with the calling line for actuating said restoring means, and separate automatically operated means for actuating said restoring means.

52. In a telephone exchange system, calling and called subscribers' lines, means including a line-switching relay for connecting a calling line with a called line, a hold- 120

- ing circuit for said relay, a contact in said circuit, means responsive to the initiation of a call for actuating said relay, manually operable means associated with the calling line for actuating said contact, and separate automatically operated means for actuating said contact. 5
53. In a telephone exchange system, calling and called subscribers' lines, means including a switch for connecting a calling line with a called line, an impulse producing means for controlling the establishment of said connection, actuating and restoring means for said switch, means responsive to the initiation of a call for operating said actuating means, manually operable means associated with the calling line for actuating said restoring means, separate automatically operated means for actuating said restoring means, and means controlled by said impulse producing means for actuating the separate automatic means. 10
54. In a telephone exchange system, calling and called subscribers' lines, an impulse producing device, means including a switch and an impulse responsive device for connecting a calling line with a called line, actuating and restoring means for said switch, means responsive to the initiation of a call for operating said actuating means, manually operable means associated with the calling line for actuating said restoring means, separate automatically operated means for actuating said restoring means, and means controlled by said impulse responsive means for actuating the separate automatic means. 15
55. In a telephone exchange system, calling and called subscribers' lines, means including a first and a second line-switching relay for connecting a calling line with a called line, variably operable counting relays for controlling the operation of the second switching relay, means responsive to the initiation of a call for actuating said first relay, a holding circuit for said first relay including a contact, manually operable means associated with the calling line for actuating said contact, separate automatically operated means for actuating said contact, and means controlled by said counting relays for actuating the separate automatic means. 20
56. In a telephone exchange system, calling and called lines, two line-switching relays, holding circuits for said relays, means responsive to the initiation of a call for actuating one of said relays to extend connections toward called lines, means individual to each calling line for opening the holding circuit of one of said switches, and a relay common to a plurality of calling lines for opening the holding circuit of one of said switches. 25
57. In a telephone exchange system, a call- ing and a called line, a switch having actuating and restoring means, means responsive to the initiation of a call for operating said actuating means to extend the calling line toward the called line, means for controlling the operation of said restoring means, and means associated with the calling line and means associated with the called line for actuating said last mentioned means. 30
58. In a telephone exchange system, a plurality of lines, a line switching relay, means responsive to the initiation of a call for actuating said relay to extend the calling line toward the called line, a holding circuit for said relay, a contact in said circuit, means associated with the calling line and means associated with the called line for actuating said contact. 35
59. In a telephone exchange system, a two-way trunk, a two-way automatic switching device at one end of said trunk, a switching device at the other end of said trunk, telephone lines, means for operating said devices to connect telephone lines with the trunk, an operator's telephone set, means for operatively connecting said telephone set with both ends of said trunk, and means for operatively connecting said telephone set with one end of said trunk. 40
60. In a telephone exchange system, a plurality of lines, a plurality of switching devices, a plurality of controlling devices, variably adjustable registering mechanisms, means controllable by a certain one of said controlling devices for adjusting said registering mechanisms, means controlled by said registering mechanisms for operating a certain switching device to select a line, and means controlled by a certain other of said controlling devices for directly effecting the actuation of a certain switching device to select a line. 45
61. In a telephone exchange system, a plurality of lines, a plurality of automatic selector switches for selecting said lines, a plurality of controlling devices, variably adjustable registering mechanisms, means controllable by only certain of said controlling devices for adjusting said registering mechanisms, means controlled by said registering mechanisms for operating a selector switch to select a line, and means controlled by only a certain other one of said controlling devices for directly effecting the actuation of a selector switch to select a line. 50
62. In a telephone exchange system, a plurality of lines, a plurality of variably operable switching devices, a plurality of controlling devices for controlling the operation of said devices to select lines, registering mechanisms interposed between a certain switching device and a certain one of said controlling devices, and a direct connection between a certain other switch- 55

ing device and a certain other controlling device.

63. In a telephone exchange system, a plurality of lines, a plurality of variably operable switching devices, a plurality of controlling devices for controlling the operation of said devices to select lines, a set of counting relays, means for operatively associating a certain one of said controlling devices with one of said switching devices through said counting relays, and means for directly associating a certain other of said controlling devices with one of said other switching devices.

64. In a telephone exchange system, a plurality of lines, a plurality of switching relays for selecting said lines, a plurality of controlling devices, variably adjustable registering mechanisms, controlling circuits extending between certain ones of said controlling devices and said registering mechanisms, actuating circuits extending between said registering mechanisms and certain ones of said switching relays, and actuating circuits extending between certain other ones of said controlling devices and certain ones of said switching relays.

65. In a telephone exchange system, a plurality of subscribers' lines, a plurality of switching devices having actuating means, an impulse producing device at each substation, an operator's position at the exchange, variably adjustable electromagnetic mechanisms at the exchange, means controllable by any one of said impulse producing devices for adjusting said mechanisms in accordance with a called line number, means operative in accordance with the adjustment of said mechanisms for actuating one of said switching devices to select a line, a variably adjustable controlling device at the operator's position, and a circuit extending from said controlling device to the actuating means of a certain one of said switching devices.

66. In a telephone exchange system, a plurality of subscribers' lines, a plurality of automatic selectors having actuating means, an impulse sending device at each substation, an operator's position at the exchange, variably adjustable impulse registering mechanisms at the exchange, means controllable by any one of said impulse sending devices for adjusting said mechanisms in accordance with a called line number, means operative in accordance with the adjustment of said mechanisms for actuating one of said selectors to select a line, a variably adjustable controlling device at the operator's position, and a control circuit extending from said controlling device to the actuating means of a certain one of said selectors.

67. In a telephone exchange system, a plurality of subscribers' lines, a plurality of

automatic line selector switches having actuating means, an impulse sending device at each substation, an operator's position at the exchange, a set of counting relays at the exchange, control circuits from said impulse sending devices to said counting relays, control circuits between said counting relays and certain ones of said switches, a variably adjustable controlling device at the operator's position, and control circuits between said controlling device and certain other ones of said switches.

68. In a telephone exchange system, a plurality of subscribers' lines, a plurality of line switching relays, an impulse sending device at each substation, an operator's position at the exchange, a set of counting relays at the exchange, control circuits from said impulse sending devices to said counting relays, actuating circuits between said counting relays and certain ones of said switching relays, a keyboard at the operator's position, and actuating circuits extending from said keyboard to certain other ones of said switching relays.

69. In a telephone exchange system, a plurality of lines, a plurality of line selector switches, a variably adjustable controlling device, means for rendering busy said lines, test contacts actuated depending on the busy or idle condition of lines, a contact at said controlling device operated in response to the adjustment of the controlling device, an electrical signal, and a circuit for said signal including said last mentioned contact and the test contacts.

70. In a telephone exchange system, subscribers' lines, a connecting circuit, digital sets of tens and units relays provided with contacts appertaining to said lines and said connecting circuit, means responsive to the initiation of a call over one of said lines for actuating one of said tens relays and one of said units relays to connect said one of said lines to said circuit, a chain of counting relays associated with said circuit, means operative over said one of said lines for setting said chain of counting relays in accordance with the designation of another one of said lines, and means dependent upon the setting of the chain of counting relays for actuating certain others of said tens and units relays to connect said connecting circuit to said other of said lines.

71. In a telephone exchange system, a subscriber's line, a connecting circuit, a plurality of tens relays and a plurality of units relays provided with contacts appertaining to said line and said circuit, actuating circuits for all of said relays, a control relay provided with contacts in all of said actuating circuits, means responsive to the initiation of a call over said line for actuating said control relay, and means operative upon the actuation of said control relay to actuate

certain ones of said first-mentioned relays to connect said line to said connecting circuit.

72. In a telephone exchange system, a plurality of lines, a switching device provided with contacts appertaining to said lines, controlling means for said device, an impulse relay for actuating said controlling means, a relay for operatively associating said impulse relay with said switching device, means for actuating said last named relay to render said impulse relay operative, means for selectively operating said switching device in accordance with the adjustment of said controlling means to select one of said lines, and means for thereupon actuating said relay to dissociate said impulse relay from said device.

73. In a telephone exchange system, a calling and a called line, a link circuit, switching means for connecting said calling line with said link circuit, other switching means for connecting the called line with said link circuit, controlling means including an impulse relay for said other switching means, means operative upon the connection of the calling line to the link circuit for connecting said impulse relay with the link circuit, and means operative upon the completion of the connection for disconnecting said impulse relay from said link circuit.

74. In a telephone exchange system, a calling and a called line, a link circuit, means for connecting the calling line with said link circuit, digital sets of selection relays for connecting the called line with said link circuit, controlling means for said selection relays including an impulse relay and a chain of counting relays, means for closing the circuit of the impulse relay upon the connection of the calling line with said link circuit, means including said impulse relay for variably operating said counting relay chain, and means for actuating said selection relays in accordance with the adjustment of said counting relay chain.

75. In a telephone exchange system, digital sets of selection relays, a chain of counting relays, an impulse relay controlling said counting relays, and means for actuating a selection relay in each set in accordance with the adjustment of said counting relays.

76. In a telephone exchange system, digital sets of selection relays, telephone lines terminating in the contacts of one of said sets of relays, variably operable controlling devices on said lines, registering devices, and means including said controlling and registering devices for selectively operating a selection relay in each set to establish telephonic connections.

77. In a telephone exchange system, digital sets of selection relays, telephone lines terminating in the contacts of one of said sets of relays, an impulse registering device, an im-

pulse relay for controlling said device, means for selectively operating said selection relays in accordance with the adjustment of said registering device, and means for thereupon opening the circuit of said impulse relay.

78. In a telephone exchange system, a set of tens relays, a set of units relays, a link circuit terminating in the contacts of said units relays, telephone lines terminating in the contacts of said tens relays, an impulse relay, a chain of counting relays controlled thereby, means for connecting said impulse relay to the link circuit at a preliminary stage of the connection, means including said impulse relay and said counting relays for actuating a tens relay and a units relay to connect the link circuit to a wanted line, and means for thereupon disconnecting said impulse relay from the link circuit.

79. In a telephone exchange system, a plurality of lines, an impulse sending device associated with each line, a plurality of connecting circuits, a plurality of counting relay sets associated with said circuits, a plurality of digital sets of selection relays in which said lines and connecting circuits terminate, means operative upon the initiation of a call for connecting an idle connecting circuit and an idle set of counting relays with the calling line, means including the impulse sending device associated with said line for adjusting the counting relays in accordance with a digit of the wanted line number, and means including said counting relays for thereupon actuating a selection relay of one of said sets.

80. In a telephone exchange system, a plurality of lines, a plurality of link circuits, sets of tens and units selection relays for connecting said lines through said link circuits for conversation, means for rendering said lines busy, testing means responsive to the busy or idle condition of said lines, a numerical register for controlling said selection relays, means for actuating certain tens and units selection relays in accordance with the adjustment of said register, means for controlling the operative association of said register with the link circuit, and means controlled by said testing means for operating said last named means.

81. In a telephone exchange system, a calling line provided with an impulse sending device, a switch, means for actuating said switch to connect the calling line to the link circuit upon the initiation of the call, means for restoring said switch upon replacing the telephone at the substation of said line, and other means including said impulse sending device for restoring said switch when desired.

82. In a telephone exchange system, two exchanges, telephone lines terminating thereat, a trunk connecting said exchanges,

connecting circuits at said exchanges, switching means at one exchange, means for actuating said switching means upon taking the telephone at a calling substation to connect the calling line with an idle connecting circuit at said one exchange, a controlling device at said calling substation, and means including said controlling device for restoring said switching means and for connecting the calling line to said trunk for an interoffice call.

83. In a telephone exchange system, two exchanges, telephone lines terminating thereat, a trunk connecting said exchanges, connecting circuits at said exchanges, tens and units line finder relays at one exchange, means for actuating said relays upon taking the telephone at a calling substation to connect the calling line with a connecting circuit at said one exchange, another set of tens and units line finder relays associated with the trunk, and means for actuating said other relays to connect the calling line with the trunk and for simultaneously restoring said first mentioned relays.

84. In a telephone exchange system, two telephone lines, a relay provided with contacts in the talking circuits between said lines, means operable at will for actuating said relay, and other means responsive to the initiation of a call for actuating said relay.

85. In a telephone exchange system, two telephone lines, a pair of relays provided with series contacts in the talking circuits between said lines, means operable at will for actuating said pair of relays, and other means responsive to the initiation of a call for actuating said relays.

86. In a telephone exchange system, telephone lines, connecting circuits, a digital set of tens and units relays provided with contacts appertaining to said lines and connecting circuits, means operable at will for actuating any of said relays, and other means responsive to the initiation of a call for actuating any of said relays.

87. In a telephone exchange system, two exchanges, a telephone line at one of said exchanges, a trunk line connecting said exchanges, tens and units relays provided with contacts through which said telephone line is extended to said trunk line, means operable over said telephone line for actuating said relays, and other means for actuating said relays at will.

88. The method of handling multi-office telephone connections comprising, first, the operation of a switch to connect the calling line with a local trunk; second, the operation of controlling devices associated with said trunk; third, the restoration of said switch with the consequent disconnection of said line from the trunk; and fourth, the operation of another switch to connect said calling line with an interoffice trunk.

89. The method of handling multi-office telephone connections comprising, first, routing the call as a local call by a non-numerical selecting operation; second, annulling said selecting operation when it appears that the call is to be an interoffice call; and third, rerouting the call directly through an interoffice channel by another non-numerical selecting operation.

It witness whereof, I hereunto subscribe my name this 12th day of March, A. D. 1920.

FRANK R. McBERTY.
